UNITED STATES PATENT OFFICE.

JACOB H. JACOB, OF PEORIA, ILLINOIS.

SPRING.

1,200,197.

Specification of Letters Patent.

Patented Oct. 3, 1916.

Application filed November 26, 1915. Serial No. 63,646.

To all whom it may concern:

Be it known that I, JACOB H. JACOB, a citizen of the United States of America, residing at Peoria, in the county of Peoria 5 and State of Illinois, have invented certain new and useful Improvements in Springs, of which the following is a specification, reference being had therein to the accompanying drawing.

10 This invention relates to springs and has for its object the production of a simple and efficient vehicle spring which is adapted to keep the body of the vehicle steady, regardless of the condition of the road over which 15 the vehicle may be traveling.

Another object of this invention is the production of a simple and efficient spring which will constitute a shock absorber and will permit the body of the vehicle to remain 20 level under all conditions, whether loaded or unloaded.

With these and other objects in view, this invention consists of certain novel combinations, constructions, and arrangements of 25 parts as will be hereinafter fully described and claimed.

In the accompanying drawings:—Figure 1 is a side elevation of the improved spring. Fig. 2 is a section taken on line 2—2 of Fig. 30 1. Fig. 3 is a top plan view of the central bar of the spring. Fig. 4 is a section taken on line 4—4 of Fig. 1. Fig. 5 is a detailed perspective of one of the plunger rods used in connection with the present spring. Fig. 35 6 is a detailed perspective of one end of one of the main springs. Fig. 7 is an embodiment of the invention showing the end plates of the spring provided with a coiled tension device for causing the end plates to remain 40 in their normal position under ordinary circumstances. Fig. 8 is a section taken on line 8—8 of Fig. 1. Fig. 9 is a section taken on line 9—9 of Fig. 1. Fig. 10 is a section taken on line 10—10 of Fig. 1. Fig. 11 is a 45 side elevation of a modification of the arrangement of the spring shown in Fig. 1. Fig. 12 is a side elevation of a still further modification of the spring shown in Fig. 1.

Referring to the accompanying drawings by numerals it will be seen that 1 designates the main sleeve which is provided with a plurality of bead portions 2 formed near the ends thereof and an arch bar or brace 3 is adapted to engage the inner bead 50 portions 2 of the sleeve 1, as illustrated in Fig. 1 of the drawings. These arch bars or

braces 3 are securely fastened at their ends 4 by means of the bolts 5 passing through the central bracing bar 6. It will be seen that these arch bars 3 will constitute an 60 efficient brace for holding the sleeve 1 in its proper position upon the bar 6. This sleeve 1 is provided with a plurality of apertures 7 formed therein as clearly illustrated in Figs. 1 and 2 of the drawings and a plunger 8 is slidably mounted within each end of the sleeve 1, as illustrated in Fig. 2 of the 65 drawings.

Each plunger 8 is provided with a shoe portion 9, which shoe portion 9 is provided 70 near each end thereof with protruding flanges 10, which flanges 10 are adapted to engage the loop 11, which loop 11 straddles the respective springs 12 and 13, as illustrated in Figs. 1 and 2, for connecting the 75 plunger rods 8 to the springs 12 and 13. These plunger rods 8 are adapted to reciprocate within the sleeve 1 as will be clearly understood by carefully considering Fig. 2 of the drawings.

80 Each of the springs 12 and 13 comprises a plurality of layers of spring or resilient strips and the outer ends of the respective springs 12 and 13 are connected to the end plates 14 and 15, by means of the bolts 16. 85 These plates 16 and 15 are in turn pivotally connected to the outer ends of the bar 6 by means of the bolts 17 so as to have a free swinging movement with respect thereto. The springs 12 and 13 are connected to suitable supports by means of the loops 18 for 90 efficiently connecting the springs to a vehicle or other supporting means.

In Fig. 7 there is shown an embodiment of the invention wherein the plates 14' and 15' are pivotally connected by means of a bolt 17' to the bar 6 and a plurality of coiled springs 19 are wound upon the bolt 17 and are adapted to retain the plates 14' and 15' in the position illustrated in Fig. 1, 100 under normal circumstances.

The operation of the device is as follows: When a load is placed within a vehicle body, supported by the springs as illustrated, the springs first being in the position shown in Fig. 1, pressure will be brought to bear. The springs 12 and 13 will thereby cause the plates 14 and 15 to be moved outwardly in the direction indicated by the arrow in Fig. 1 at the same time spreading the springs 12 and 13. The plungers 8 of course will be moved inwardly within the sleeve or casing 110

1 but the sleeve or casing 1 will be firmly held in its proper position with respect to the bar 6 by means of the bracing members 3. As soon as pressure is relieved from the 5 spring, the parts will of course assume their normal position.

From the foregoing description it will be seen that a very simple and efficient means has been produced for permitting the 10 springs to be relieved of considerable pressure or weight in view of the fact that some of the expanding action will take place by means of the outer ends of the plates 14 and 15 being moved outwardly.

15 It of course should be understood that the plates 14 and 15 may be removed and longer plates substituted therefor if so desired, to accommodate the different weights adapted to be carried by the vehicle body, 20 supported upon the springs illustrated.

It should be understood that the spring 13 is adapted to be secured to the axle and is always the same distance from the ground, but it should be further understood that if 25 any sudden jolt from the wheels should occur, the spring 13 would have a tendency to move toward the spring 12 thereby causing the outer ends of the plates 14 and 15 to be spread apart and limit the downward movement of the spring 12 with respect to the 30 spring 13.

In Fig. 11 there is shown an embodiment of the invention wherein a primary spring or rod 20 is employed, carrying a toggle arm 21, which toggle arm 21 is pivotally secured to a toggle arm 22. This toggle arm 22 engages the lower primary spring 23. The toggle arms 22 carried by each end of the primary springs 20 and 23 are connected to 40 link arms 24 and 25 respectively and these link arms 24 and 25 are connected to the upper and lower auxiliary springs 26, as illustrated in Fig. 11. It will be seen that when 45 pressure is brought to bear upon the top spring, the inner ends of the arms 21 will be moved downwardly, thereby raising the lower ends of the arms 21 and causing the outer end of the links 24 to be moved outwardly under the pressure which is brought 50 to bear upon the spring.

In Fig. 12 there is shown still another embodiment of the present invention wherein a primary upper spring or rod 27 is employed connected to an arc-shaped toggle 55 arm 28, the arc-shaped toggle arm 28 being pivotally connected to an arc-shaped toggle arm 29 carried by the lower primary spring 30. Each of the toggle arms 28 and 29 is 60 pivotally connected to a link 31, the links 31 being connected to the outer or auxiliary springs 32 and 33, as illustrated.

What I claim is:-

1. A device of the class described comprising a plurality of spaced spring members, a longitudinally extending central bar,

links connected to said central bar and being pivotally connected to said spring members and being adapted to be forced outwardly as said spring members are compressed toward each other. 70

2. A device of the class described comprising a plurality of spaced spring members, a central bracing member, link members pivotally secured to said bracing members and having their outer ends pivotally secured to said spring members, for causing the outer ends of said link members to be moved outwardly as said spring members are compressed, and bracing means engaging said central portion of said spring members. 80

3. A device of the class described comprising a plurality of spaced spring members, a longitudinally extending bracing member, links pivotally secured to the outer ends of said longitudinally extending bracing member and having their outer ends inwardly inclined and connected to the outer ends of said spring members, and the outer ends of said link members being adapted to be forced upwardly as pressure is brought 90 to bear upon said spring members. 85

4. A device of the class described comprising a plurality of spaced spring members, a longitudinally extending bracing member, links pivotally secured to the outer ends of said longitudinally extending bracing member and having their outer ends inwardly inclined and connected to the outer ends of said spring members, and the outer ends of said link members being adapted to be forced upwardly as pressure is brought 100 to bear upon said spring members, and bracing means engaging the central portion of said spring members. 95

5. A device of the class described comprising a plurality of spaced spring members, a longitudinally extending bracing member, links pivotally secured to the outer ends of said longitudinally extending bracing member and having their outer ends inwardly inclined and connected to the outer ends of said spring members, and the outer ends of said link members being adapted to be forced upwardly as pressure is brought 110 to bear upon said spring members, a sleeve carried by said central brace member, plungers engaging said spring members, and braces carried by said central brace member and engaging said sleeve. 115

6. A device of the class described comprising a plurality of spring members, a longitudinally extending bracing member, a sleeve carried by said central bracing member, plungers engaging said spring members and working in said sleeve, and arch braces engaging said sleeve and said brace member for holding said sleeve in a rigid position with respect to said central brace member. 126

7. A device of the class described comprising a plurality of spring members, a 130

longitudinally extending bracing member, a sleeve carried by said central bracing member, plungers engaging said spring members and working in said sleeve, and arch braces 5 engaging said sleeve and said brace member for holding said sleeve in a rigid position with respect to said central brace member, each plunger provided with laterally extending feet, flanges carried by the ends of said 10 feet, and means engaging said flanges for securing said feet to said spring.

8. A device of the class described comprising a plurality of spring members, a central bracing member, links pivotally connected to said central bracing member and 15 also pivotally connected to said spring members, and coiled springs engaging said links for normally urging said links in an inwardly inclined position.

In testimony whereof I hereunto affix my signature.

JACOB H. JACOB.
